UNITED STATES PATENT OFFICE.

EDWARD M. KEMP, OF RHINELANDER, WISCONSIN.

DESIGN FOR A STOVE-BOARD.

SPECIFICATION forming part of Design No. 35,382, dated December 3, 1901.

Application filed August 22, 1901. Serial No. 72,960. Term of patent 14 years.

To all whom it may concern:

Be it known that I, EDWARD M. KEMP, a citizen of the United States, residing at Rhinelander, in the county of Oneida and State of Wisconsin, have invented and produced a new and original Design for a Stove-Board, of which the following is a specification, reference being had to the accompanying drawing, forming part thereof.

It is the object of my invention to provide a new ornamentation for a stove-board; and my design is represented in the accompanying drawing, which shows a plan view of a stove-board having a background, center-piece, and border simulating a mosaic tiling.

The double border A is practically rectangular in form and tessellated.

The centerpiece B consists of an essentially circular figure inclosing a small central one which is formed of a series of rings b, arranged concentrically and overlapping each other, as shown.

The mosaic background C extends over the entire space inclosed by the border A.

The design proper is fully shown only in a quarter-section of the figure.

What I claim is—

The design for a stove-board substantially as shown and described.

EDWARD M. KEMP.
